UNITED STATES PATENT OFFICE.

FRITZ ALDENDORFF, OF WILMERSDORF, BERLIN, GERMANY.

METERING TELEPHONE SYSTEM.

Carved out of application on which Patent No. 1,319,031 was granted October 14, 1919, and filed after grant of that patent. This application filed June 21, 1920. Serial No. 390,320.

(GRANTED UNDER THE PROVISIONS OF THE ACT OF MARCH 3, 1921, 41 STAT. L., 1313.)

To all whom it may concern:

Be it known that I, FRITZ ALDENDORFF, a citizen of the German Republic, residing at 32 Mannheimerstrasse, Wilmersdorf, Berlin, 5 Germany, have invented certain new and useful Improvements in Metering Telephone Systems (for which applications have been filed with my consent in Germany on the 15th of November, 1913, by the Gesellschaft 10 für elektromechanische Telephonapparate m. b. H., in Berlin-Wilmersdorf, and in England, by Harold Baron, on the 8th of December, 1913, and on which applications a German Patent No. 322,248 issued on 26th 15 of June, 1920, and an English Patent No. 28,291 of 1913, was accepted on the 15th of July, 1915), and of which the following is a specification.

My invention relates to electromechanical 20 or automatic or semi-automatic switching systems. It relates more specifically to meter arrangements in a system of the kind described in my application Serial No. 814451, filed Jan. 26, 1914, Patent No. 1,319,031. 25 The present application contains the same disclosure and is filed after the grant of said patent.

An object of the invention is to economize 30 switches. This object is attained by providing switches which act according to the requirements of the moment as line finders or as connectors; in other words these switches at times connect a calling line to a free trunk leading to another switch such as a group 35 selector or connector and other times they extend a connection which has advanced to a certain stage to the wanted subscriber's line. Switches which act both as line finders and connectors are known, but the novelty in 40 the scheme described herein consists in the manner in which the trunks or link circuits are connected to these switches and in their specific arrangement and circuits. They are provided with sets of fixed contacts 45 connected to subscribers' lines and with a set of movable contacts or brushes capable of being brought into contact with any of their sets of fixed contacts. From the set of brushes of each of these switches (which will 50 henceforth be called "two-way" switches because they extend connections from calling subscribers to a trunk and at other times from a trunk to a subscriber) one trunk or

link circuit leads to the movable contact arms of a group selector or a selector finder 55 and another trunk leads to the fixed contacts of a group selector or selector finder. The set of brushes of each two-way switch is connected whilst the switch is in its normal position to the movable contact arm of the 60 group selector or selector finder with which it is associated. But as soon as the two-way switch is to be used for establishing a connection with a wanted subscriber its brushes are disconnected from the contact arm of the 65 group selector or selector finder associated with it and are connected to the trunk extending to the fixed contacts of the group selectors or selector finders.

The brushes of some of the two-way 70 switches are directly connected to group selectors whilst others are connected to group selector finders which establish connections with free group selectors.

The two-way switches are started or set in 75 motion one after the other by starting impulses sent through a starting circuit in the order in which the calls are made by the calling stations.

The moment a subscriber calls the battery 80 lead to the calling or line circuits of the other subscribers is opened by a "call regulator" until a connection is made between the calling subscriber and a group selector or connector. The line relay of each subscriber 85 has a locking circuit which is closed the moment the subscriber calls in order to render the calling circuit of this subscriber independent of the common battery lead which is opened immediately after the call is made. 90

Whenever a two-way switch is moved out of its normal position in order to establish a connection with a calling line the starting circuit is disconnected from this switch and is immediately extended to the next two-way switch. This also takes place whenever a two-way switch is used for connecting with a wanted line. For these two cases two special switches are provided one of which is shifted by the two-way switch 95 itself as soon as it is moved out of its normal position, the other being shifted independently of its two-way switch by a current from a group selector over the trunk leading to the two-way switch. 100

The starting circuits of the two-way 105

switches are arranged so that the starting of several switches by the same starting impulse is impossible. This is accomplished by arranging the switch that extends the 5 starting circuit from one two-way switch to the next so that the starting circuit is extended only after a starting impulse has ceased flowing. The extending switch has a spring which is tensioned by a magnet 10 excited by the starting impulse and which only exerts its force so as to shift the extending switch after the starting impulse has ceased flowing.

In large exchanges the subscribers' lines 15 are divided into groups and each group of lines is connected to a group of two-way switches. The groups of subscribers' lines are sub-divided into sub-groups. Each two-way switch is composed of two finders, a 20 primary and a secondary finder. The primary finder finds the calling line and the secondary finder finds the sub-group in which the calling line is contained. In order to hasten the action of the two-way 25 switch when finding a calling line its primary and secondary finders are arranged to act simultaneously. Permutation wires are provided for each group of subscribers which are connected to contacts of all the 30 primary and secondary finders of the group and which, at the moment a subscriber calls, determine the points at which the finders of the two-way switch used for the call shall stop in order to extend the calling line to a 35 group selector or link circuit. If there are ten sub-groups and ten lines in each sub-group the greatest number of steps to be taken by the primary and secondary finders will be ten and as both finders act simultaneously the maximum time required for 40 finding any particular line out of 100 is the time that the brushes of a finder take to travel the distance occupied by ten adjacent sets of contacts.

45 When a two-way switch is used to make a connection with a wanted line the circuits of the motor magnets of the primary and secondary finders of the switch, which are ordinarily connected to a common circuit, 50 are separated and the motor circuits are then controlled separately by the person setting up the connection with the aid of a switch controller.

55 The primary and secondary motor circuits of a two-way switch are separated also when restoring the switch to its normal position.

The two-way switches are each provided 60 with two test relays, one for the primary finder and another for the secondary finder, which open the circuits of the finder motor magnets the moment they find the proper permutation wire. These test relays are made inoperative when the two-way switch 65 is used to connect to a wanted line.

Another feature of the invention consists in an impulse repeater located at a group selector at which impulses arising in one portion of a circuit are repeated in another portion of the circuit, the second portion 70 being normally disconnected by open contacts from the first and the open contacts not being closed until the called subscriber in responding to the call changes the strength of the ringing current sent to him 75 from a group selector.

In order to simplify the circuits of the last selector in an established connection (i. e. of the selector or connector that makes connection with the wanted line) no circuits are 80 used in this selector which act backwardly on the impulse repeater at the group selector. A called subscriber in responding to a call influences the impulse repeater at the group selector without the aid of any intervening devices or circuits placed at the last selector. This is accomplished by tentatively applying a source of ringing current through 85 a ringing control electromagnet or relay located at the group selector to leads extending through a chain of selectors to the wanted line. The arrangement of the ringing control circuits is such that if the wanted line is busy and the test relay in the last or final selector is not excited, no ringing 90 current flows through the said ringing control magnet on account of the ringing current path to the wanted line not having been closed by the said test relay. If the line is busy the ringing current does not flow. 95 Whether the ringing current remains connected to the leads or not is made dependent on its flowing immediately after it is connected to the leads. If the ringing current does not immediately commence flowing 100 a relay at the group selector which effects the steady application of the ringing current to the leads fails to be energized and the momentarily applied ringing current is then disconnected by the detraction of the 105 armature of a slow acting relay. If the relay which causes the steady application of the ringing current is energized it closes the circuit of a ringing cut-off relay. The ringing current passes through the windings 110 of this relay but does not cause it to attract its armature until the called subscriber responds to the call and causes a strengthening 115 of the ringing current. When the ringing cut-off relay is thus energized it closes 120 the circuit of a connecting relay which closes the contacts that separate the calling half of the circuit from the called half and also prepares a meter circuit which is closed 125 when the connection is broken at the end of the conversation. The energization of the ringing cut-off relay also results in the cutting off of the ringing current.

The invention is illustrated in the accompanying drawing in which Fig. 1 shows the 130

general connecting plan of the new system. Fig. 2 shows the circuits of the subscriber's line relays, the arrangement of the permutation or guide wires of the two-way switches 5 and the arrangement of the call regulator. Figs. 3 and 4 illustrate the circuits of the two-way switches which perform the two functions of connecting a calling line to a group selector and of connecting a trunk leading from the fixed contacts of a group selector to a wanted line. Fig. 5 shows the circuits of the selector finders designated HS in Fig. 1. Fig. 6 illustrates the circuits of a first group selector with an impulse repeater and 15 Fig. 7 shows the circuits of a second group selector. By placing Figs. 2 to 7 beside each other with Fig. 2 at the left and Fig. 7 at the right end a diagram of the complete system forming the subject of this invention 20 will be obtained. Figs. 8 and 9 illustrate certain contacts used in my apparatus.

In Fig. 1 the three first groups of one hundred subscribers of an exchange for 1000 lines are diagrammatically indicated. To 25 the right of the bracket I are indicated the switching apparatus VS^I, HS^I and GW^I of the first hundred group. The switching apparatus of the second and third hundred groups are shown at the right of the brackets 30 II and III.

It will be assumed that there are 15 two-way switches (only ten shown) in each group which in the cases of calls coming from the subscribers S to the exchange connect 35 the calling subscribers to free group selectors GW and in the cases of connections extended by group selectors GW to trunks h_1 , h_2 etc. connect these trunks to the lines of the wanted subscribers.

40 Each two-way switch VS is shown by three arcs 1, 2, 3 and a movable contact or brush 4. Each arc 1, 2, 3 is supposed to represent a row of ten sets of fixed contacts. In reality each two-way switch has ten rows 45 of ten sets of contacts in each but to simplify the drawing and description only three rows are indicated.

The lines of three subscribers S^I₁, S^I₂, S^I₃—S^{II}₁, S^{II}₂, S^{II}₃—S^{III}₁, S^{III}₂, S^{III}₃, connected to the third contact rows of the two-way switches are indicated.

50 Of the 15 two-way switches in each group 5 are connected directly to group selectors GW and 10 are connected to group selectors 55 by means of selector finders HS to any idle one of a group of 15 group selectors. The latter group is made up of 5 groups selectors in each of the three hundred groups.

60 The 10 selector finders HS^I endeavour to pass calls first to the lower 5 group selectors GW^I. If these are all busy they test consecutively 3 of the lower five group selectors GW^{II} and if these are busy also they proceed to test 2 of the lower 5 selectors GW^{III}.

65 In a similar manner the selector finders

HS^{II} test first the lower 5 group selectors GW^{II}, then 3 selectors GW^{III} and finally 2 selectors GW^I. The selector finders HS^{III} test first five selectors GW^{III}, then 3 GW^I and finally two GW^{II}.

70

Of the contact rows of the group selectors only three are indicated by the arcs p , s , t ; each row of contacts is multiply connected to a trunk cable h_1 , h_2 which contains the trunk wires leading to the fifteen movable contacts 4 of the particular group of the two-way switches.

75

The trunk cable h_1 leads to the two-way switches VS^I of the first hundred group, the trunk cable h_2 to the two-way switches VS^{II} of the second hundred and h_3 to the switches VS^{III} of the third hundred etc.

80

The path of a talking connection through the system will now be illustrated: Suppose a subscriber S^I calls. The brush 4 of a disengaged two-way switch will immediately move into contact with the line of the calling subscriber and will connect this line to a group selector. This connection to a group selector GW will be either direct or through a selector finder HS^I. The calling subscriber S^I or a semi-automatic operator will now cause the movable contact 5 of the group selector to select the row of fixed contacts that corresponds to desired hundred group e. g. the row leading to the second hundred II that is connected to the trunk cable h_2 .

85

The group selector now hunts automatically for a free two-way switch VS^{II}. When this is found the person controlling the switches causes the brush 4 of two-way switch VS^{II} to be moved into contact with the wanted subscriber's line, e. g. S^{II}₃.

90

95 As the two-way switches VS are used both for outgoing connections originating at the subscribers' stations and for incoming connections which come to the subscribers' stations from other stations and serve the double purpose of line finders and connectors, a considerable saving of switches is accomplished.

100

105 In the known systems in which separate line finders and connectors are used it will happen that all the line finders of a group are busy whilst some of the connectors of the group are still free. Further calling subscribers would not be able to make connections as all the line finders are busy.

110

115 But in the new system with two-way switches that will do the work of line finders or connectors according to the requirements of the moment the further calling subscribers will still be able to make connections as long as any two-way switches are idle.

120

125 If at any moment the demand for connectors is in excess of the demand for line finders this demand will be supplied in a similar way. Thus with the same number of switches more connections can be 130

made in the busy hour or with the same connecting capacity fewer switches can be used.

Fig. 2 indicates the circuits of the subscribers of a hundred group. Each hundred group is sub-divided into tens groups and S_{11}, S_{12} represent the first two subscribers of the first tens group, S_{21}, S_{22} the first two subscribers of the second tens group and S_{31}, S_{32} the first two subscribers of the third tens group. The other subscribers are omitted in order to simplify the drawing.

If the subscriber S_{12} calls, his line $12^a, 12^b$ must be connected through the movable contacts ba, bb, bc — ba^1, bb^1, bc^1 of the two-way switch, Fig. 3, to a trunk line va, vb, vc which leads directly or indirectly (through a selector finder HS, Fig. 5) to a first group selector GW^1 .

20 The brushes ba, bb, bc — ba^1, bb^1, bc^1 of the two-way switches VS are set or guided to the positions in which they establish a connection between the trunk va, vb, vc and the calling line (represented in this case by the contacts KS_{12}) by guide wires or permutation wires pu, pt .

The guide wires are divided into two groups pu, pt one of which guides the primary finder to the contact representing the calling line, the other guiding the secondary finder to the contact representing the tens group in which the calling line is contained. When a subscriber calls, his line relay e. g. lr_{12} is energized and it earths one wire in each of the groups of guide wires pt and pu thus setting up a circuit combination which will cause the proper motions of the primary and secondary finders of the next free two-way switch in the particular hundred group for connecting the calling line to a trunk.

45 The calling of the subscriber S_{12} i. e. the second subscriber in the first tens group results in the contacts 100, 101 of his line relay lr_{12} earthing the first wire l^{11} of the tens group of guide wires pt and the second wire 2^1 of the units group of guide wires. If the subscriber 11 calls his line relay contacts earth the first tens guide wire l^{11} and the first units guide wire l^1 . A call from subscriber No. 21 would result in the earthing of the tens wire 2^{11} and the units wire l^1 and so forth, so that a certain combination of earthed guide wires corresponds to each of the hundred subscribers of the group.

55 In Fig. 3 only the circuits of one two-way switch VS is shown but the permutation or guide wires pt, pu lead to all the two-way switches of the hundred group and are connected to each of these switches by branch wires w_1, w_2, w_3, w_4, w_5 — p_1, p_2, p_3, p_4, p_5 . The contact sets ks of the two-way switches of a group are connected in multiple.

60 From the common call regulator AR of each group a starting wire SW extends to the first two-way switch VS. As soon as

this switch is taken into use its starting wire SW is extended through a switch 104 or 103 to an extension starting wire SW_1 which leads to other switches similar to 103, 104 on the next two-way switch. If the second two-way switch of the group is also engaged the starting wire is extended to the third two-way switch and so forth.

The primary finder of each two-way switch has ten sets of three brushes each ba, bb, bc and a guiding brush pb , all these brushes being driven so as to brush past sets of contacts ks and single contacts K respectively by a common driving shaft D. If the brushes are moved so as to make the guiding brush pb rest upon the guiding contact k_2 , each of the sets of brushes ba, bb, bc will rest upon the second sets of contacts ks in the row of contact sets $ks_{10}, ks_{20}, ks_{30}$, etc., that it rides over. If the brush pb were to be moved to the fourth guiding contact k_4 each of the sets of brushes ba, bb, bc would also be moved to the fourth set of contacts ks in its particular row and so forth.

The common driving device that moves all the brushes consists of a ratchet wheel ZR fixed to a shaft D which is rotated step by step by a pawl kl oscillated by an electromagnet EM.

The shaft D also shifts a switch OS_1 which whilst the two-way switch is in its normal position opens the contacts 104, 110—105, 108—106, 107 and closes the contact 104, 108. The moment the two-way switch leaves its normal position the contacts 106, 107—105, 108—104, 110 are closed and the contact 104, 109 is opened.

Only one set of brushes ba, bb, bc will be connected to the trunk va, vb, vc when a connection has been extended through the two-way switch. The set of brushes to be connected to the trunk is selected by the secondary finder ZW which has ten sets of fixed contacts Kz of four contacts each and a set of four movable brushes ba^1, bb^1, bc^1, sb . The set of brushes ba^1, bb^1, bc^1, sb is driven in any suitable manner e. g. by a shaft D^1 which is turned with the aid of a ratchet wheel ZR^1 by a pawl KL^1 oscillated by the armature Am^1 of the secondary finder driving magnet ZM .

The chain of events which happen when a subscriber calls and establishes a connection with another subscriber will now be explained.

Suppose subscriber No. S_{12} calls and establishes a connection with the subscriber No. 3465.

On raising his receiver from his switchhook the calling subscriber causes the two limbs $12^a, 12^b$ of his line to be connected in a well-known manner and a current then flows through the subscriber's loop the path of which may be traced from the battery B through the armature 112 of the call reg-

ulator, thence through 113, 114, 12^a, S₁₂, 12^b, 115 to earth. The line relay *lr*₁₂ attracts its armature closes a locking circuit for itself through the contact 116. By closing its contact 117 the line relay closes the circuit of the call regulator AR (battery B, AR, 117, earth) and this attracts its armature and by opening the contact 112 opens the common battery feeder of all the line relays of the 100 hundred group to which the calling subscriber belongs, so that no other subscriber of the same group can make a call by closing his loop and energizing his line relay until a two-way switch VS has connected the first 15 calling subscriber to a group selector. The connecting operation of the two-way switch will, however, not require more than about $\frac{1}{2}$ a second so that if the second subscriber calls immediately after the first the delay in taking up his call will be so short that he will 20 not notice it. The purpose of the momentary cutting off of the battery feed to all the subscribers except the first to call is to prevent a mixing of the calls and a wrong setting of the two-way switches which would 25 be possible if more than one call were passed on to the two-way switches at a time. For this reason the sequence in which the calls are passed on over the starting wire SW is 30 regulated so that the calls are transmitted over the starting wire one after the other.

By its contacts 100, 101 the line relay *lr*₁₂ earths the first tens guide wire *l*¹¹ and the second units guide wire *2*¹ so that the contacts *k*₂ and *z* in all the two-way switches of the group will be earthed and the points indicated where the brushes *sb* and *sp* of the particular two-way switch used are to stop.

The call regulator in attracting its armature causes a momentary closure of the contact 119, 120. The armature 118 brushes past the spring 119 and momentarily presses 40 119 against 120. When the armature falls back into its normal position 119 is pressed 45 away 120 and no closure of contact 119, 120, takes place.

It is thus seen that the moment the subscriber S₁₂ calls a current impulse is sent by the momentary closure of the contact 50 119, 120 from the battery B through SW. If the two-way switch VS is idle this impulse will flow through 103, 111, 154, 104, 109, 155, 116, 156 to 157. At the point 55 157 the starting impulse divides into three parts the one part flowing through 131, 158, motor magnet ZM of the secondary finder, 159 to earth and another part through 131, 160, 115, 161, 162, motor magnet EM of the primary finder, 163 to earth and the 60 third part through 164, 135, *ah*, 200, 201, 203, starting relay to earth. The magnets ZM and EM attract their armatures and each shifts its pawl (*kl* and *kl*¹) into the next tooth of its ratchet wheel ZR, ZR¹. 65 When the starting impulse through contact

119, 120 ceases the pawls *kl* and *kl*¹ are drawn back to their normal positions by their springs 165, 166 and the ratchet wheels ZR, ZR¹ are turned one step as a result of which the sets of brushes *ba*, *bb*, 70 *bc* and the brush *pb* and also the brush set *ba*¹, *bb*¹, *bc*¹, *sb* are shifted. The movement of the shaft D out of its normal position also causes the off-normal switch OS₁ to be shifted and the first two-way switch VS of 75 the group to be cut-off from the starting circuit 154 at contact 104, 109 and to be connected to an interrupter 168. The starting circuit 154 is simultaneously extended through contacts 104, 110 and through SW₁ 80 to the next idle two-way switch of the group so that the starting impulse caused by the subscriber that calls next will flow through the magnets ZM and EM of the next idle two-way switch. 85

The motor magnets of the started two-way switch will now be energized by current impulses which flow from the negative pole of the exchange battery through 168, 105, 108, 155, 118, 156, 157, 131, 158, 90 ZM, 159 to earth and through 131, 160, 115, 161, 162, EM, 163 to earth respectively. As soon as the brush *pb* reaches the contact *k*₂ of the second units guide wire *2*¹ which is earthed by the armature contact 101 a current will flow through the test relay *pr* from the negative pole through 117, 169, 134, 170, *pr*, 171, *pb*, *k*₂, *2*¹, 172, 101 to the positive pole. The test relay *pr* is energized and opens the circuit of the primary finder magnet EM at 163 so that the sets of brushes *ba*, *bb*, *bc* now all rest upon the second contact sets in their respective rows. 95

The set of brushes *ba*¹, *bb*¹, *bc*¹, *sb* is moved at the same time as the brush sets 105 *ba*, *bb*, *bc* and as soon as the test brush *sb* strikes the tens guiding contact *z*₁ which is earthed by the armature contact 100, a current will flow through the secondary test relay *sr* from the negative pole through 117, 169, 134, 170, *sr*, 174, *sb*, *pl*, *l*¹¹, 173, 100 to earth. This will energize the secondary test relay which will open motor magnet circuit thus causing the set of brushes *ba*¹, *bb*¹, *bc*¹, 110 *sb* to stop at the first contact set *k*₂. 115

In the case assumed in which the twelfth subscriber of the hundred group is calling the circuit of the secondary finder magnet will be opened immediately after the starting impulse has flowed, because the moment 120 this impulse ceases the brush set *ba*¹, *bb*¹, *bc*¹, *sb* will be advanced to the first set of contacts *k*₂ of the secondary finder.

The first contact set *k*₂ is connected to the first set of brushes *ba*, *bb*, *bc* counting 125 from the right, so that the calling subscriber S₁₂ will now be connected through *a*₁₂, *b*₁₂, *c*₁₂, *ks*₁₂, the first set of branches *ba*, *bb*, *bc*, the first contact set *k*₂, brush set *ba*¹, *bb*¹, *bc*¹ to the trunk *va*, *vb*, *vo*.

The moment the test relays *pr*, *sr* are both energized, the contacts 132, 133 will be closed and a current will flow from the negative pole through 132, 133, 125, connecting relay 5 *tr*, 124 to the positive pole. The relay *tr* closes its contacts 141, 142, 143 and thus extends the wires *va*, *vb*, *vc* to the wires *va*₁, *vb*₁, *vc*₁. The relay *tr* also closes and opens a number of other contacts, but these are 10 only of importance when the two-way switch *VS* is used as connector and need not be regarded in connection with the line finding operation of the two-way switch.

It was mentioned above that the starting relay 205 of the selector finder *HS*, Fig. 5, was energized at the same time as the motor magnets *EM* and *SM* by the starting impulses sent through the starting wire *SW* at the moment the subscriber *S*₁₂ called. When 15 the relay 205 is energized the contacts 202, 203 are opened and the contacts 204, 208, 207 closed. By its contact 204 the relay 205 closes a locking circuit for itself which is independent of the starting circuit *ah* and 20 may be traced from the negative pole through 213, 204, 205 to earth. By its contact 208 the relay 205 closes the circuit of test relay *prh* and by its 207 the circuit of the turning or motor magnet 206 of the selector finder (negative pole, interrupter 218, 210, 206, 207, earth). The turning magnet 206 now rotates the brushes *wa*, *wb*, *wc* by a ratchet and pawl arrangement in a well-known manner causing them to brush over 25 the fixed contacts connected to the trunks *va*₂, *vb*₂, *vc*₂, until an idle trunk is reached. A current then flows from the negative pole through 208, 211, *prh*, *wc*, *vc*₂, relay *er*, 219 to earth. The relays *prh* and *er* are energized. 30 The relay *prh* opens the circuit of the motor magnet 206 at its contact 210 so that the brushes *wa*, *wb*, *wc* stop on the fixed contacts connected to the trunk *va*₂, *vb*₂, *vc*₂ leading to an idle first selector *GW*¹. 35 By its contact 212 the test relay closes a locking circuit for itself which is independent of the contact 208 and at its contact 213 it opens the circuit of the starting relay 205. By its contacts 214, 215, 216 the test 40 relay extends the line of the calling subscriber to the first group selector *GW*¹. The relay *prh* opens the contact 217 and thereby prevents a premature release impulse from flowing from the earth through 209, 202 to 45 the release wire *al*. By the opening of contact 200 unnecessary oscillations of the armature of the starting relay are prevented which would be caused by impulses flowing from the interrupter 168 through 108, 155, 50 118, 156, 164, 135 and *ha*.

When the calling line is extended to the group selector by the closure of the contacts 214, 215, 216 the cut-off relay *cr*₁₂ of the calling subscriber is energized by a current flowing from the positive pole of the battery 55

through 219, *er*, Fig. 6, *vc*₂, *wc*, 216, *vc*₁, 123, 143, *vc*, *bc*₁, *bc*, *c*₁₂, *cr*₁₂ to the negative pole. Through the test relay *prh* and the cut-off relay *cr*₁₂ being connected in parallel the test potential on the test wire *vc*₂ is lowered to 70 such an extent that further test relays *prh* which may be brought into connection with the trunk *va*₂, *vb*₂, *vc*₂ will now not receive sufficient current to energize them so that the trunk *va*₂, *vb*₂, *vc*₂ will appear engaged. 75

By the energization of the cut-off relay *cr*₁₂ the line relay *lr*₁₂ is cut off from the calling line. On the deenergization of the line relay *lr*₁₂ the earth connections of the guide wires 1¹¹ and 2¹ are removed and at 80 the same time the call regulator *AR* is deenergized by the opening of contact 117. When the call regulator is deenergized it does not close the contact 120, 119, but it reconnects the battery *B* to the contacts 112 85 of all the line relays *lr* of the group so that the call of the next subscriber will now be taken and passed on to the next idle two-way switch.

The time that elapses from the moment 90 the subscriber calls to the moment when the two-way switch *VS* and the trunk selector *HS* have established the connection between the calling subscriber and the group selector only amounts to a fraction of a second so 95 that the likelihood of two calls waiting to be taken up is extremely remote and if it occurs the second subscriber to call will not notice any delay.

As soon as the earth connections of the 100 guides wires 1¹¹, 2¹ are removed through the cutting off of the line relay *lr*₁₂ the circuits of the test relays *pr*, *sr* will be broken and the contacts 163, 159 in the circuits of the motor magnets *EM* and *ZM* will be closed. 105 But these circuits will now be kept open at the contact 131 of the connecting relay *tr*.

It has been said that when the brushes *wa*, *wb*, *wc* are caused to stop on the idle trunk *va*², *vb*², *vc*², relay *er* is energized that 110 is associated with this trunk. The relay *er* serves to close the battery circuit of the relays *rr* and *cr*. The relay *cr* is a circuit shifting or "change over" relay which 115 changes over the group selector from its selecting to its trunk hunting or testing function. The relay *rr* is a release relay which closes the release circuits of the selectors when the subscriber replaces his receiver on its switchhook. 120

The relays *rr* and *cr* are energized in the periods of time during which the armature of the line control relay travels from one extreme position to another. The relays *rr* and *cr* are energized by opening contacts 125 232 and 233 and thereby opening paths of low resistance by which they are usually short-circuited. For this reason the battery circuits of these relays must be closed before the selecting impulses commence actu- 130

ating the line control relay 280. This closure is effected by the contact 220 of the relay *er*.

On the calling line being extended to the trunk line va_2 , vb_2 , vc_2 the line control relay 280 is immediately energized by a current flowing from the negative pole of B^1 through the lower winding of 280, vb_2 , wb , 214, ob_1 , 121, 142, vb , bb_1 , bb , b_{12} , S_{12} , 12^a, 10 a_{12} , ba , ba^1 , va , 141, 119, va^1 , 215, wa , wa_2 , upper winding of 280 to earth.

Just before the energization of relay 280 the relay *er* was energized by a current flowing from the negative pole through 220, 232, 15 *er* to earth. In attracting its armature the relay *er* lets the spring 236 press against the contact spring 237. On the energization of the relay 280 the relay is short circuited by contact 233 and allows its armature to drop 20 back whereupon the negative battery pole is momentarily connected to the "change over" circuit 290. This circuit is, however, still open at the contact 238 so that so far no shifting of circuits will be caused by applying 25 the negative battery pole to the wire 290 belonging to the change over circuit.

When the relay 280 is energized the relay *rr* is energized by the opening of its short circuit at contact 232 the current flowing 30 through *rr* from the negative pole through 220, *rr*, 233 to earth.

As the calling subscriber desires a connection with subscriber No. 3465 he will work his switch controller in a well known 35 manner so as to first cause three openings of his line loop in rapid succession. This will cause three oscillations of the armature of the line control relay 280. During these oscillations the relays *rr* and *er* are short 40 circuited only for very brief moments for the contacts 232, 233 are adjusted so as to be closed only whenever the armature of 280 has moved to its utmost limit. These brief short-circuitings of the relays *rr* and 45 *er* are not sufficient for these relays to allow their armatures to fall back so that they keep then attracted.

Each time the armature of 280 drops back a current impulse is sent through the vertical magnet 246 of the up and around group selector from the negative pole through 220, 231, 234, 224, 246 to earth. The vertical magnet 246 lifts the wipers of the group selector, which will be assumed to be 55 of the Strowger type, to its third row of fixed contacts.

After the three thousand selecting impulses have thus been sent in by the three rapid openings of the calling subscriber's line loop this loop remains steadily closed for a while until the subscriber sends in the next series of impulses for selecting the wanted hundred. The steady closure of the line loop causing an attraction of the line control 60 relay armature and the change over relay

er will then be short circuited long enough to cause to release its armature. During the falling of this armature the contact springs 237 and 291 will be connected for a moment. When the armature of *er* has fallen entirely 70 back the spring 291 will press the spring 236 away from 237 thus breaking the connection between 237 and 291. Whilst the connection lasts a current will flow from the negative pole through 220, 230, 237, 236, 291, 290, off-normal switch 238, which is closed when the wipers are lifted out of their normal position, 226, 247 to earth. This energizes the rotary magnet 247 which turns the wipers *ga*, *gb*, *gc* of the group selector round 80 one step and thereby causes the rotary off-normal switches 255 and 256 to be closed. The switch 256 connects an interrupter 257 to the rotary magnet so that impulses now commence flowing from the negative pole 85 through 257, 256, 229, 226, rotary magnet 247 to earth and the rotary magnet causes the brushes to travel over the sets of fixed contacts connected to trunks va_3 , vb_3 , vc_3 until a trunk leading to an idle second group 90 selector GW^{II} is reached when a current will flow from the positive battery pole through the test relay 248, test wiper *gc*, vc_3 , 300 to earth.

The test relay 248 and the release relay 95 300 of the second group selector both attract their armatures. The former opens its contact 229 and thus interrupts the circuit of the motor magnet 247 and by its contacts 226, 227 it also shifts the change 100 over circuit 290 from the rotary magnet to a relay 249. The stepping or measuring circuit 295 is shifted from the vertical magnet 246 to the brush *ga* the connection to the brush *ga* being made through contacts 105 225 and 270.

By its contact 228 the test relay 248 short circuits a part of its winding and thereby reduces the potential on the test vc_3 to such an extent that no other first group selector 110 will be able to establish a connection with the second group selector GW^{II} .

An idle group selector in the third thousand group now being selected and found the calling subscriber proceeds to select the desired fourth hundred group by causing four interruptions of his line loop with the aid of his switch controller. This causes four oscillations of the line control relay armature and each time this armature falls back an impulse flows from the negative pole through 220, 231, 234, 295, 225, 270, *ga*, va_3 , 307, vertical magnet 305 to earth. The vertical magnet moves the brushes *ga*, *gb*, *gc* of the second group selector GW^{II} up to the 115 fourth bank contact row. When the brushes are raised out of their normal position a contact 303 is closed which prepares the circuit of the release magnet 304 which is open 120 at this time at the contact 302.

After the calling subscriber has caused the series of four interruptions of his line loop another interval ensues during which the loop is steadily closed and the line control relay armature is steadily attracted. The change over relay *cr* is then steadily short circuited by the contact 233 of the line control relay and allows its armature to drop back and to close the change over circuit which may be traced from the negative pole through 220, 230, 237, 236, 291, 290, 238, 227, relay 249 to earth. The relay is energized and sends a change over impulse from the negative pole through 252, 296, 277, *gb*, *vb*, 15 312, 313, 310, rotary magnet 306 of the second group selector *GW^{II}* to earth. The rotary magnet immediately turns the brushes *ga*, *gb*, *gc* one step and thus causes the opening of off-normal contact 313 and 20 the closing of off-normal contact 315. The impulse sent over the wire *vb*, thus causes the immediate opening of the change over circuit 296, 277, *gb*, *vb*, etc. at the contact 313 and the closure of an independent circuit for the rotary magnet by the contact 315.

When the change over relay 249 was energized it not only closed the change over circuit but also the circuit of a slow-acting relay 250 (negative pole, 253, 250 to earth). This relay closes a contact 254 and when on the immediate opening of the change over circuit 290, the relay 249 is deenergized, the ringing current source 268 is applied through 258, 254, 251, 296, 277 to the line *vb*, until the slow-acting relay allows its armature to fall back so as to cut off the ringing current at its contact 254. Although the ringing current is applied to the line *vb*, no ringing current will flow because the change over circuit from 296, 277, *gb*, *vb*, 35 312, 313, 310, 306 to earth was interrupted the moment the relay 249 attracted its armature and sent an impulse through the rotary magnet 306 causing the contact 313 to be opened in the manner already explained.

The circuits are so arranged that a closed circuit through which ringing current will flow upon the ringing machine being applied 40 through 296 to the line *vb*, will be found only after the final selector (connector) has made connection with the wanted line and has found this line idle. Under these circumstances the ringing current machine will 45 send ringing current to the called subscriber until this subscriber in responding to the call removes his receiver from its switchhook and thereby causes the ringing current to be strengthened sufficiently to energize a relay 264 at the group selector which then causes the ringing current to be cut off and the calling and called ends of the talking circuit to be connected together by a relay 273.

In the known circuit combinations for automatically stopping the flowing of ringing

current the application of ringing current to the wanted line is made dependent on the test relay of the final selector or connector. According as the wanted line is idle or busy the test relay will cause ringing current to 70 be applied to it or not. If it were desired with circuits of this kind to place the ringing current source at a group selector some special circuits would have to be provided by which the influence of the test relay at the 75 final selector is transmitted back to the group selector in order to connect the ringing current to the wanted line.

By this invention these special circuits for reacting from the test relay of the final 80 selector upon the means at the group selector for connecting the ringing current are avoided. According to this invention the ringing current is applied momentarily to the line which is being extended to the wanted subscriber at each change over impulse. The permanent connection of the ringing current to the line is, however, made dependent on the line extending to the wanted subscriber being found closed. If the line is found 85 closed the ringing current will actually flow and in flowing it causes circuit changes at the group selector which result in the tentative application of the ringing current being converted into a steady connection of the 90 same which lasts until the wanted subscriber responds to the call.

It has been previously explained that the disconnecting of the tentatively applied ringing machine 268 is effected by the dropping back of the armature of the slow-acting relay 254 shortly after the closure of the circuit of the rotary magnet 306 of the second group selector *GW^{II}* because on account of the opening of contact 313 no closed 100 circuit exists in which a ringing current can flow from the ringing machine. The circuits by which the ringing machine is steadily connected in the case of being applied to a 105 closed circuit will be explained later.

The rotary magnet 306 which is energized by current impulses from the negative pole through 314, 315, 310, 306 to earth turns the wipers *g^a*, *g^b*, *g^c* of the second group selector causing them to brush over sets of the fixed bank contacts leading to the fifteen two-way switches VS through trunks *a₃₀₀*, *b₃₀₀*, *c₃₀₀* until an idle trunk is reached. If a trunk *a₃₀₀*, *b₃₀₀*, *c₃₀₀* is idle the two-way 110 switch Figs. 3 and 4 associated therewith 115 will be in its normal position and its contact 130 will be closed.

The trunk *a₃₀₀*, *b₃₀₀*, *c₃₀₀* to which the group selector *GW^{II}* extends the connection of the calling subscriber will, of course, 120 lead to a different two-way switch than the one whose brushes are connected to the calling line. But as the circuits of all the two-way switches are alike the events which 125 take place at this stage of the connection 130

of the calling subscriber may be explained with the aid of Figs. 2, 3, 4.

The two-way switches of the selected hundred group which are already being used for other connections will appear busy to the hunting group selector on account of their switches 130 being open. The moment the brushes of the group selector strike a free trunk a current will flow through the test relay pr_2 from the negative battery pole through 301, pr_2 , gc , c_{300} , converging relay SR of the idle two-way switch in the desired hundred group, closed switch 130 to earth. The relays pr_2 and SR are both energized. The former opens the circuit of the rotary magnet 306 at its contact 310 and by closing its contact 309 it short circuits a part of its winding and thus lowers the potential on the test wire c_{300} so as to render the seized trunk busy. By closing its contacts 308, 311 the test relay pr_2 extends the talking circuit va_3 , vb_3 to the two-way switch Figs. 3 and 4.

The converting relay SR by shifting its armature contacts converts the two-way switch from a line finder to a final selector. By opening its contact 111 and closing the contact 112 it disconnects the starting wire SW from the seized two-way switch and extends it to the wire SW_1 leading to the next two-way switch in the hundred group so that the next call arising in this group will be passed on to this next two-way switch. By closing its contact 113 the converting relay connects the change over wire b_{300} to the change over devices 190, 193 which at a later stage change the connection of the selecting wire a_{300} from the tens or secondary motor magnet ZM to the units or primary motor magnet EM of the two-way switch. By the closure of contact 114 the selecting wire a_{300} is connected to the tens magnet ZM (through 139, 160, 158, ZM, 159 to earth). By opening of contact 115 the circuits of magnets ZM and EM which are ordinarily connected to the common wire 193 leading from the interrupter 168 are separated so that now each of these motor magnets can be controlled separately. At the contact 116 the release wire leading to the associated selector finder or group selector is broken in order that when this wire is earthed on the breaking down of the connection in the manner to be described a momentary closure of the circuit of the rotary magnet is prevented. This momentarily closed circuit would extend from the negative pole through 218, 210, 206, 202, 217, a^1 , 195, 194, 129, 128 to earth. At the contact 117 the battery lead to the relays pr , sr is opened in order that, when the brushes of the two-way switch are moved into connection with the wanted line, the touching of earthed guide wires by the brushes pb , sb will not cause the said relays to be ener-

gized. At contact 118 the battery lead from the interrupter 168 to the wire 164 is disconnected in order to prevent impulses flowing through 118, 164, 135, ha , 200, 203 to the starting relay 205 of the selector finder HS on the shifting of the switch OS_1 which happens when the two-way switch is moved out of its normal position. The contact 107 opens current path from the selecting wire a_{300} through 139, 131, 164, 135, 200 to the starting relay 205 and at contacts 119, 121, 123, the lines va_1 , vb_1 , vc_1 leading to the selector finder are disconnected. Through contacts 120, 121 the talking wires in the two-way switch are disconnected from the selector finder and connected to the trunk extending from the last group selector in the partly established connection of the calling subscriber.

By the opening of the contact 124 the ordinary circuit of the test relay tr is broken and this relay is converted by the opening of the contact 125 and closure of contact 126 into a test relay for testing the condition of the wanted line that will presently be selected by the two-way switch. By closing the contact 127 the converting relay SR closes a locking circuit for itself which is independent of the switch 130. Finally the converting relay SR moves on being energized the contact spring 129 but in so doing no connection is made between the contacts 129, 128. These contacts are closed only when the relay SR is deenergized and they then cause the energization of a release relay rl as will be more fully described later. The contacts 116, 129, 128 are so adjusted that the contact 116 is closed only after the contact between 129, 128 is opened so as to prevent an impulse flowing from earth through 128, 129, 195, 116, 217, 202 to the rotary magnet 206 of the selector finder.

When the converting relay SR is energized and has produced the circuit changes just described the calling subscriber sends in the tens selecting impulses by causing a number of interruptions of his line loop that corresponds to the tens digit of the wanted line which in this case is "6." The line control relay 280, Fig. 6, lets its armature execute six oscillations. Each time the armature falls back an impulse flows from the negative battery pole through 220, 231, 234, 295, 225, 270, ga , va_3 , 308, g^1a , a_{300} , 114, 139, 158, tens motor magnet ZM, 159 to earth. By these six impulses the set of brushes ba^1 , bb^1 , bc^1 of the two-way switch is stepped round to the sixth set h_2 which is connected to the sixth brush set i. e. the set of brushes ba , bb , bc , that travels over the contact sets h_5 in the sixth row or sixth tens group. The desired tens group is now selected.

In order to select the individual line in the selected group of ten lines all the brush

sets ba , bb , bc of the two-way switch are moved five steps. The sixth brush set ba , bb , bc will then rest upon the fifth set of bank contacts in its contact row this being 5 the set of bank contacts that belongs to the wanted line No. 3465. The desired line is now selected.

The other nine sets of brushes ba , bb , bc will also each be resting on the fifth contact sets ks in their respective rows, but these brush sets have no connection with a brush set ba^1 , bb^1 , bc^1 so that they do not establish any connection with the subscribers' lines on which they are resting.

15 A detailed description of the switching functions which take place in setting the brushes ba , bb , bc of the two-way switch onto the desired line will now be given.

After the series of tens selecting impulses 20 is sent in the calling subscriber's loop is again steadily closed and the steady short circuiting of the change over relay cr caused hereby results in the falling back of the change over relay armature. A change 25 over impulse then flows from the negative pole through 220, 230, 237, 236, 291, 238, 290, 227, relay 249 to earth. The relay 249 attracts its armature and closes a circuit extending from the negative pole through 252, 296, 277, gb , vb_3 , 311, g^1b , b_{300} , 113, Fig. 4, 30 152, change over relay 190 to earth. The change over relay is energized and immediately opens the change over circuit at 152 so that the ringing machine 268 applied 35 to the change over circuit through 254, 251 can not send out any ringing current and will be cut off again by the dropping back of the armature 254 of the slow-acting relay.

40 The change over relay 190 closes a locking circuit for itself from the negative pole through 151, 153, 190 to earth. The switch 151 is closed when the secondary finder ZW is moved out of its normal position.

45 At its contact 139 the change over relay separates the selecting wire a_{300} from the secondary motor magnet ZM and connects it through contact 138 and through 196, 162 to the primary motor magnet EM.

50 On the calling subscriber now sending the five units selecting impulses the armature of the line control relay 280 drops back five times and five units selecting impulses flow through 220, 231, 234, 295, 225, 55 270, ga , va_3 , 308, g^1a , a_{300} , 114, 138, 196, 162, primary motor magnet EM, 163 to earth, these impulses causing the brush sets ba , bb , bc to be moved to the fifth bank contact sets and to select the desired subscriber's 60 line in the manner already described.

65 After the last series of selecting impulses has gone in the line control relay 280 keeps its armature steadily attached so as to de-energize the change over relay cr again by short circuiting it. The relay 249 is then

momentarily energized and a test impulse flows from the negative pole through 252, 296, 277, gb , vb_3 , 311, g^1b , b_{300} , 113, switch 150 which is closed the moment the primary finder is moved out of its normal position, 70 149, relay 193 to earth. The relay 193 is energized and by opening contact 149 disconnects itself from the change over wire b_{300} . But it also closes a test circuit extending from the positive pole through 198, 75 146, 147, relay tr , 126, cv , bc^1 , bc , test wire c_{3465} (not shown in the drawing but similar to the test wire of the calling subscriber) cut off relay cr of the desired line No. 3465 to the negative pole of the exchange battery. 80 If the wanted line is free the relay tr , which now acts as a test relay, will be immediately energized and will extend the lines a_{300} , b_{300} to the line of the wanted subscriber by closing its contact 141, 142. The ringing 85 machine, which is applied by the contact 254 of the slow-acting relay to the line b_{300} after the change over impulse sent through contact 252 ceases, now sends out a ringing current before the slow-acting relay 90 lets its armature drop back. The ringing current flows from the earth through 268, relay 258, 254, 251, 296, 277, gb , vb_3 , 311, g^1b , b_{300} , 121, 142, vb , bb^1 , bb , b_{3465} , 3465b, bell of wanted subscriber No. 3465, 3465a, 95 a_{3465} , ba , ba^1 , va , 141, 120, a_{300} , g^1a , 308, va_3 , ga , 270, 225, 295, 298 to earth.

By the immediate flowing of the ringing current the steady connection of the same to wanted line is effected by means of a relay 258 which is energized by the ringing current and closes a ringing current path which is independent of the contact 254 of the slow-acting relay, this path leading through 259, 260, right hand winding of 100 relay 299, 296, 277 to the above-described ringing circuit. The relay 299 is now energized and the circuit including relay 258 is broken at 260 which causes the relay 258 to open its armature contact 259 and to 105 permanently disconnect itself.

The ringing current is now kept connected to the wanted line by the relay 299 which closes the contacts 261, 262 before opening the contact 260. If the interrupter 115 267 which is continually running just happened to have closed its contact 265 the ringing current will flow from 268 through 265, 264, 261, right hand winding of 299, 286, 277 to the wanted subscriber's ringing 120 circuit. But if the interrupter happens to have closed the contact 266 at the moment the relay 258 is cut off, the ringing current will not flow through the line of the wanted subscriber but through 266, 263 and the 125 left winding of 299. It is thus seen that in any case the one or the other winding of 299 is energized. If the contact 265 is closed the ringing current flows through the relay 264 and the right hand winding of 130

299 to the wanted line, but if the contact 266 is closed the whole ringing current flows through the left winding of 299 and there will be a pause in the ringing of the wanted subscriber's bell.

When the called party responds by removing his receiver from his switchhook the ringing current flowing through the relay 264 is strengthened sufficiently to cause this 10 relay to close its armature contact 263. A current then flows from the negative pole through 263, connecting relay 273 to earth. The relay 273 thereupon interrupts the flow of ringing current at 277 so that the energization of the right winding of 299 ceases before the left winding is reenergized. The relay 299 is therefore deenergized and the ringing machine 268 is cut off at 261, 262.

By closing its contacts 271, 276 the relay 20 273 extends the line of the calling subscriber to that of the called subscriber and disconnects selecting and change over circuits at contacts 270 and 277.

The relay 273 closes a locking circuit for 25 itself by its contact 272 (negative pole, 255, 272, 273, earth) and by its contact 269 it momentarily short circuits a part of the winding *er* and thus momentarily strengthens the current in the meter circuit (*vc*₂, *vc*₁, 30 123, 143, *vc*, *bc*¹, *bc*, *c*₁₂, *z*₁₂, negative pole) so as to make the meter *z*₁₂ attract its armature and register the conversation.

In order to cause the meter circuit to be 35 only momentarily closed by the energization of the relay 273 so as not to impair the busy condition of the test wire *vc*₂, the contact 269 is made like the contact 119, 120 of the call regulator AR, Fig. 2. This is more clearly 40 shown in Figs. 8 and 9. In Fig. 8 273 represents the end of the armature that is moved in the direction indicated by the arrow 274' when the relay 273 is energized. The end of the armature is round and glides along the right hand oblique surface at the 45 end of the contact spring 269 so as to move 269 towards the left and against the contact spring 269. When the armature is fully attracted its end will be located above 269 as indicated by the dotted circle 273''. On 50 the deenergization of the relay 273, the round end 273' glides along the left side of the oblique end of 269 forcing it further away from 269' instead of towards 269'. The affecting of the busy condition of the 55 line *vc*₂ can also be prevented by using a contact 119, 120 which causes the momentary closure of the meter circuit on the deenergization of relay 273 at the finish of the talking connection. In this case a similar 60 arrangement to that illustrated in Figs 8 and 9 is used, but the end of the armature is arranged so as to push the spring 269 away from 269' when it is attracted and to push it against 269' when it falls back. In 65 other words the end of 269, instead of run-

ning in a slanting direction from its top end downwards towards the left, would run in a slanting direction from its top end downwards towards the right.

When the calling and called ends of the 70 talking circuit are connected at the contacts 271, 276 a circuit is closed including the relays 278, 279 and extending from earth through 278, 271, *ga*, *va*₃, 308, *g*¹*a*, *a*₃₀₀ to the two-way switch which has established the 75 connection with the wanted line, 120, 141, *va*, *ba*¹, *ba* of the sixth set of brushes, *a*₃₄₆₅, 3465*a*, *S*₃₄₆₅, 3465*b*, *b*₃₄₆₅, *bb*, *bb*¹, *vb*, 142, 122, *b*₃₀₀, *g*¹*b*, 311, *vb*₃, *gb*, 276, 279 to the negative pole. The relays 278, 279 are excited; 80 279 closes its armature contact 240 and 248 opens its contact 239.

The calling subscriber is now connected to the called subscriber over the following path: *S*₁₂, 12*a*, *a*₁₂, *ba*, *ba*¹ of the two-way 85 switch which has connected to the calling line, *ba*¹, *va*, 141, 119, 215, *wa*, *va*₂, *co*₁, 271, *ga*, *va*₃, 308, *g*¹*a*, *a*₃₀₀, two-way switch VS in the called hundred group, contact 120 of the converting relay SR of this switch, 141, *va*, 90 *ba*¹, *ba* of the sixth set of brushes of the two-way switch, *a*₃₄₆₅, 3465*a*, *S*₃₄₆₅, 3465*b*, *b*₃₄₆₅, *bb*, *bb*¹, *vb*, 142, 122, *b*₃₀₀, *g*¹*b*, 311, *vb*₃, *gb*, 276, *co*₂, *vb*₂, *wb*, 214, *vb*₁, 121 of the two-way switch that has connected to the calling 95 line, 142, *vb*, *bb*¹ *bb* of this switch, *b*₁₂, 12*b*, *S*₁₂.

If the calling subscriber is the first to 100 terminate the connection by replacing his receiver on its switchhook and thereby opening his line loop the line control relay 280 will be deenergized and the release relay *rr* will be steadily short circuited. The latter relay will then allow its armature to drop back and close the release circuit (earth, 105 235, 245, 223, negative pole). The release magnet 245 will be energized and will cause the first group selector to be restored to its normal position. The release magnet also opens its armature contact 222 and thereby 110 deenergizes the relays *er* and *prh*. The relay *prh* lets its armature drop back, thus opening its locking circuit at its front contact 212 so that, until the starting relay 205 is energized again, no reenergization of the 115 relay *prh* can take place. By the contact 210 the circuit of the rotary magnet 206 of the selector finder is closed (negative pole, 218, 210, 206, 209, earth) and this magnet now rotates the brushes *wa*, *wb*, *wc* in a 120 forward direction, until they reach their normal position, when the off-normal switch 209 will be opened and the circuit of the rotary magnet 206 interrupted.

The deenergization of relay *prh* causes 125 the closure of its armature contact 217 and the completion of the release circuit of the two-way switch VS which made the connection with the calling line this release circuit extending from earth through 209, 202, 130

217, *al*, 116, 195, relay *rl* to the negative pole. The release relay *rl* of the two-way switch is thus energized and closes a locking circuit for itself which may be traced from 5 the negative battery pole to *rl*, 137, 107 to earth. At its contact 136 the release relay opens the locking circuit of the relay *tr*. This relay is then deenergized and closes at its back contact 131 the circuit of the magnet EM (negative pole, 168, 108, 155, 118, 157, 131, 115, 162, EM, earth) which remains closed until the driving device D of the primary finder reaches its normal position and disconnects the interrupter 168 10 from the motor magnet EM by opening the contact 108.

The motor magnet ZM of the secondary finder is completely disconnected from the circuit of the motor magnet EM of the 20 primary finder at contact 195¹ of the restoring relay *rl* in order that the two finders may move independently of each other into their normal position.

The independent restoring circuit of the 25 motor magnet ZM is closed by the contact 196¹ of the restoring relay *rl* and extends from the negative pole to interrupter 197¹, 196¹, 167¹, ZM, 159 and to earth. The moment the secondary finder reaches its normal position the contact 167¹ is opened and the motion of the finder is stopped through the interruption of the circuit of the magnet ZM.

In order to prevent interruptions of the 35 circuits of the magnets EM, ZM by energizations of the test relays *pr*, *sr* caused during the travel of the brushes *pb*, *sb* into their normal positions by their striking earthed guide wires the battery lead to these 40 relays is kept open by the contact 134 of the restoring relay *rl* until this relay is deenergized. The restoring relay is, however, not deenergized until the two-way switch reaches its normal position and opens the 45 locking circuit of the restoring relay *rl* by severing the contacts 107 and 167.

To prevent the flowing of impulses from 168 through 108, 155, 118, 156, 164, *ha*, 200 to the starting relay 205 when the relay *prh* is deenergized and the contact 200 closes the armature contacts of *prh* are so adjusted that 200 remains open until shortly after the closure of 217 i. e. until shortly after the energization of *rl* and until the opening of 135 by *rl*. By this means current impulses are prevented from flowing from 168 through 108, 155, 118, 156, 164 to the starting wire *ha* during the restoration of the two-way switch which would cause a displacement of the selector finder HS.

The second group selector GW^{II} is released as soon as the first group selector is restored and its brush *gc* breaks its connection with the trunk wire *vc₃*. The relay 300 of the second group selector is then deenergized and

closes the circuit of the release magnet 304 (negative pole, 302, release magnet 304, 303, earth) which thereupon releases the second group selector. At the moment the release circuit is closed the test circuit *pr2* is opened 70 at 301 so as to prevent any energization of the test relay *pr2* whilst the brush *g¹c* travels over the bank contacts of other trunks *c₃₀₀* during the restoration of the selector.

The moment the contact arm *g¹c* of the 75 second group selector leaves the trunk *c₃₀₀* leading to the called hundred group the converting relay SR of the two-way switch in this group that was used for the talking connection is deenergized and on its armature falling back the contact 128, 129 is momentarily closed. This causes the energization of the restoring relay *rl* associated with this two-way switch, the restoring circuit extending from earth, 128, 129, 194, *rl* to the 80 negative pole.

The deenergization of the converting relay SR results in the opening of the circuit of the test relay *tr* (earth, 140, *tr*, 126, *vc*, *bc*, 90 *bc*, *c₃₄₆₅*, *cr₃₄₆₅*) by the contact 126.

The two-way switch used for establishing the connection with the wanted subscriber is now restored in the same manner as the two-way switch that connected to the calling line, the restoring functions of which have 95 already been described.

It will be remembered that the magnet EM is energized by impulses from the negative pole through 168, 108, 118, 157, 131, 115, 162, EM, 163 to earth and that the magnet ZM receives its restoring impulses from the negative pole through 197¹, 196¹, 167¹, ZM, 159 to earth.

If the called subscriber is the first to replace his receiver on the switchhook at the 105 end of the conversation the restoration of the switches, selectors etc. will be initiated by the deenergization of the relays 278, 279. The relay 279 is slow-acting and lets its armature drop back later than the relay 278. The deenergization of these two relays will thus result in a short closure of a release circuit from earth through 240, 239, 245, 223. The release magnet 245 is thus energized and caused to restore the first group selector 110 GW^I to its normal position and to initiate the restoration of the switches in the connection extending towards the calling subscriber and towards the called subscriber.

Instead of using a slow-acting relay 279 120 and a quick acting relay 278 for the act of restoring by the called subscriber a single relay provided with contacts like 119, 120 of the call regulator may be used. This contact could be arranged to be closed not when the restoring relay (e. g. 278) is energized but when this relay lets its armature drop back. If the wanted line is busy at the moment the two-way switch is set onto the wanted line the relay *tr* will not be energized 125 130

as previously described and hence the talking leads of the calling subscriber will not be connected through the contact 141, 142 to the line of the wanted subscriber.

5 A feature of the meter circuits used in the present system which was not mentioned in the above description will now be pointed out:

10 It was shown that the actuation of the meter of the calling subscriber is caused by strengthening the current flowing in the wire c_{12} , this strengthening being produced by partially short circuiting the winding of relay er by means of contact 269. Now when 15 a two-way switch is used to establish a connection with a wanted line, the energization of the relay tr of this switch and the partial short-circuiting of this relay will also produce a strengthening of the current 20 in the wire c_{3465} of the called subscriber. But the alteration of the current strength will be balanced by the resistances w_{100} , w_{101} so as to prevent the called subscriber's meter being actuated.

25 Mention will now be made of a detail regarding the ringing and change over circuits:

30 It will be remembered that the change over relay 249 is deenergized for a moment at the end of each series of selecting impulses and momentarily connects the negative pole through 252 and 277 to the change over wire. Immediately afterwards, on the dropping back of the armature of 249, the 35 ringing current machine 268 is connected through 254, 251, 277 to the change over wire, but a current does not flow through it because the contact 313 is immediately opened by the operation of the rotary magnet 306. But it is possible that the group 40 selector GW^{II} will find the first or second trunk a_{300} idle and that in such a case the test relay pr_2 will very soon extend the change over wire vb_3 to the final two-way 45 switch by closing the contact 311. This extension of the change over wire would then possibly take place before the slow-acting relay 250 reopens its contact 254 and disconnects the ringing machine. This would 50 result in the steady application of the ringing machine to the change over circuit because a ringing current would flow from earth through 268, 258, 254, 251, 296, 277, gb , vb_3 , 311, g^1b , b_{300} , 113 (this contact 55 would be closed by the energization of SR) 152, 190 to earth. In order to prevent this undesirable flowing of ringing current a switch is preferably provided at the point 199¹ indicated by the cross in the two-way 60 switch which is closed only when the calling subscriber commences to send in his tens selecting impulses. By that time the slow-acting relay 250 will be sure to have found time to open its contact 254. The switch at 65 point 199¹ may consist of a contact comprising

ing two springs similar to 167 which closes the moment an impulse is sent through the tens magnet ZM .

70 It was assumed in the case of the above connection between a calling and a called subscriber that a two-way switch that is associated with a selector finder extended the calling subscriber's line to a first group selector. If, at the time the calling subscriber makes a call, the next idle two-way switch 75 in the group is one that is connected directly to a first group selector, all the events in the establishment of the connection between the calling and called subscribers will be as described above except that the functions 80 of the selector finder will be omitted. The lines va_1 , vb_1 , vc_1 will in this case not pass through contacts 214, 215, 216 and brushes wa , wb , wc but will be directly connected to an associated first group selector and the 85 starting wire extending from point 157 through 135 will be unnecessary.

90 The release wire al instead of passing through contact 217 will be connected directly to an armature contact of the release magnet 245 of the first group selector and on the energization of the release magnet the restoration of the two-way switch will be initiated by the earthing of the restoring 95 wire al .

95 Another point will be mentioned in connection with regulating of the incoming calls by the call regulator. It will be remembered that the call regulator ordinarily prevents two calls from being simultaneously passed on to the two-way switches of a hundred group. The call regulator will perform its function perfectly as long as not more than two calls come in at the same or almost the same instant: This will generally be 100 all that is required in a practical system. That three or more calls will come in at the same instant is almost out of question. Even this contingency can however be provided for by arranging a special relay common to each 105 group of subscribers which will be excited if more than one subscriber calls in the interval of about $\frac{1}{2}$ a second during which a two-way switch is in the act of making a connection with a calling line. The special common 110 relay will then cause relays, of which one is associated with each of the lines that happens to call in the above mentioned interval, to be energized and to connect these lines to a special signal, whilst disconnecting them from their line relays and thus 115 preventing two or more subscribers from simultaneously earthing the guide wires and possibly causing ineffective line finding operations of the two-way switches. The special signal would cause the subscribers 120 who sent in simultaneous calls to hang up their receivers and to thus restore their lines to their normal idle condition. The subscribers would then wait a few seconds be- 125 130

fore making their connections. Means by which the special signal may be given are known in the art, so that a detail description of the same appears unnecessary.

5. I claim:—

1. In a system for interconnecting lines by electro-mechanically controlled switches, calling lines, wanted lines, switch controllers, numerical switches controlled by said controllers, trunk hunting switches for hunting for idle numerical switches, two-way switches of which some are associated with certain of the said numerical switches and others with certain of the said trunk

10 controllers, trunk hunting switches for hunting for idle numerical switches, two-way switches of which some are associated with certain of the said numerical switches and others with certain of the said trunk hunting switches, non-numerical means for setting a two-way switch onto a calling line, means controlled by said controllers for setting a two-way switch onto a called line, a meter associated with each line, and circuits in said two-way switches for actuating said

15 meters.

2. In a system for interconnecting lines by electro-mechanically controlled switches, calling lines, wanted lines, switch controllers, numerical switches controlled by said controllers and having fixed and movable contacts, trunk hunting switches for hunting for idle numerical switches, two-way switches of which some are permanently as-

20 sociated with certain of said numerical switches and others with certain of said trunk hunting switches, a trunk leading from the movable contact of each two-way switch to the fixed contacts of numerical

25 switches, non-numerical means for setting a two-way switch onto a calling line, means controlled by said controllers for setting a two-way switch onto a called line, a meter associated with each line, and circuits in

30 said two-way switches for actuating said meters.

3. A telephone system comprising subscribers' stations, an electro-mechanically controlled telephone exchange, lines connecting said stations to said exchange, switch controllers, switches at said exchange each having rows of fixed contacts, a primary member for cooperating with each fixed contact row, a secondary member for

35 cooperating with said primary members, means for operating said primary members and secondary member simultaneously and means for operating the secondary member and primary members successively in response to said switch controllers, meters associated with said lines, and circuits in said switches for actuating said meters.

4. In a telephone switching system, electro-mechanically controlled switches for interconnecting telephone lines, subscribers' lines, switch controllers, switch controlling circuits each having only two conductors extending said controllers to said switches, groups of fixed contacts on said switches, movable contacts on said switches, group se-

lecting means responsive to said switch controllers for putting movable contacts into engagement with any desired group of fixed contacts, contact selecting means responsive to said controllers for putting movable contacts into connection with any desired individual contact in a group, means for causing the act of selecting a group of contacts and of selecting an individual contact in a group to be carried out simultaneously, 75 meters associated with said lines, and circuits in said two-way switches for actuating said meters.

5. In a system for interconnecting lines by electro-mechanically controlled switches, 80 subscribers' lines, switch controllers, numerical switches controlled by said controllers and having fixed and movable contacts, multi-row switches each having a plurality of rows of fixed contacts and movable contacts for engaging with any of said contact rows, a trunk connected to the movable contacts of each multi-row switch, a device for connecting the said trunk at times to the fixed contacts of numerical switches and at other times to the movable contacts of numerical switches, meters associated with said lines, and circuits in said multi-row switches for actuating said meters. 95

6. In a system for interconnecting lines by electro-mechanically controlled switches, meters associated with said lines, switch controllers, numerical switches controlled by said controllers and having fixed and movable contacts, trunk hunting switches for hunting for idle numerical switches, multi-row switches each having a plurality of rows of fixed contacts and movable contacts for engaging with any of said contact rows, 100 a trunk connected to the movable contacts of each multi-row switch, a device for connecting said trunk at times to the fixed contacts of numerical switches and at other times to trunk hunting switches, and circuits in 105 the numerical and multi-row switches for actuating said meters.

7. In a system for interconnecting lines by electro-mechanically controlled switches, subscribers' lines, meters associated with said lines, switch controllers, numerical switches controlled by said controllers and having fixed and movable contacts, trunk hunting switches for hunting for idle numerical switches, multi-row switches each having a 110 plurality of rows of fixed contacts and movable contacts for engaging with any of said contact rows, trunks connected to the movable contacts of the multi-row switches, devices for connecting some of said trunks at 115 times to the movable contacts of numerical switches and at other times to the fixed contacts of numerical switches, devices for connecting others of said trunks at times to the movable contacts of numerical switches and 120 125 130

- at other times to trunk hunting switches, and means in the multi-row switches and numerical switches for establishing circuits therethrough for said meters.
5. 8. In a system for interconnecting lines by electro-mechanically controlled switches, telephone stations, meters assigned to said stations, numerical switches having fixed and movable contacts, multi-row two-way switches each having a plurality of rows of fixed contacts and movable contacts for engaging with any of said contact rows and adapted to connect a calling telephone station to the movable contact of a numerical switch and to connect the fixed contact of a numerical switch to a called telephone station, and circuits in said multi-row switches and numerical switches for actuating said meters.
20. 9. In a system for interconnecting lines by electro-mechanically controlled switches, telephone stations, meters assigned to said stations, numerical switches having fixed and movable contacts, multi-row two-way switches each having a plurality of rows of fixed contacts and movable contacts for engaging with any of the said contact rows and adapted to connect a calling telephone station to the movable contact of a numerical switch and to connect the fixed contact of a numerical switch to a called telephone station, a starting circuit for starting the action of said two-way switches in succession, two independent devices on each two-way switch for extending the starting circuit from one two-way switch to another, and circuits in said multi-row and numerical switches for actuating said meters.
10. In a system for interconnecting lines by electro-mechanically controlled switches, telephone stations, meters assigned to said stations, numerical switches having fixed and movable contacts, multi-row two-way switches each having a plurality of rows of fixed contacts and movable contacts for engaging with any of said contact rows and adapted to connect a calling telephone station to the movable contact of a numerical switch and to connect the fixed contact of a numerical switch to a called telephone station, circuits in said numerical switches for enabling a numerical switch to seize an idle two-way switch, a starting circuit for starting the action of said two-way switches in succession, two independent devices for each two-way switch for extending the starting circuit from one two-way switch to another, the one independent device being actuated on the seizure of its two-way switch by a numerical switch, and circuits in said multi-row and numerical switches for actuating said meters.
11. In a system for interconnecting lines by electro-mechanically controlled switches, telephone stations, meters assigned to said stations, switch controllers, trunk hunting switches for hunting for idle numerical switches, multi-row two-way switches of which some are associated with certain of said numerical switches and others with certain of said trunk hunting switches, said multi-row switches each having rows of fixed contacts, a primary member for cooperating with said rows, a secondary member for cooperating with said primary member, a primary test relay associated with said primary member, a secondary test relay associated with said secondary member, means for rendering said test relays inoperative, and means in said numerical and multi-row switches for actuating said meters.
12. In a system for interconnecting lines by electro-mechanically controlled switches, stations, switch controllers, meters assigned to said stations, numerical switches controlled by said controllers, trunk hunting switches for hunting for idle numerical switches, two-way switches associated with said trunk hunting switches and having terminals leading to the stations, and means in the numerical and two-way switches for actuating said meters.
13. In a system for interconnecting lines by electro-mechanically controlled switches, calling stations, wanted stations, meters assigned to said stations, switch controllers, numerical switches controlled by said controllers, two-way switches with terminals connected to said stations, means for effecting connections through the two-way switches at times in a direction from said stations to the numerical switches and at other times in a direction from said numerical switches to said stations, and means in the two-way switches for actuating a meter only when the station to which it is assigned is a calling stations.
14. In a system for interconnecting lines by electro-mechanically controlled switches, subscribers' stations with calling means, meters assigned to said stations, two-way switches having fixed and movable contacts, lines connecting the subscribers' stations to the said fixed contacts, means for setting the movable contacts of a two-way switch onto the fixed contacts of a calling subscriber's station, a source of current, a current-impulse-sending switch controller at a calling subscriber's station, a motor magnet for moving the movable contacts of a two-way switch onto the line of a wanted subscriber, means for controlling the motor magnet by impulses set up by a switch controller, and means in the two-way switches for actuating a meter only when the line to which it is assigned is a calling line.
15. In a system for interconnecting lines by electro-mechanically controlled switches, two-way connecting switches with fixed and movable contacts, calling lines, wanted lines,

- meters associated with said lines, means for shifting said movable contacts onto calling lines, means for shifting said movable contacts onto wanted lines, an automatic testing means associated with each two-way switch for preventing the automatic establishing of a connection between a calling line and a busy wanted line, and means in each two-way switch for actuating a meter only when 5 the switch has connected to a calling line.
16. In a system for interconnecting lines by electro-mechanically controlled switches, two-way connecting switches with fixed and movable contacts, calling lines, wanted lines, 10 meters assigned to said lines, means for shifting said movable contacts onto calling lines, means for shifting said movable contact onto wanted lines, a source of ringing current, means for applying ringing current 15 to a wanted line, an automatic testing means associated with each two-way switch for preventing the automatic establishing of a connection between a calling line and a busy wanted line and for preventing the 20 flow of ringing current to a busy line, and means actuating only the meters of calling 25 lines.
17. In a system for interconnecting lines by electro-mechanically controlled switches, 30 calling lines, wanted lines, two-way connecting switches for connecting calling lines and wanted lines, meters assigned to said lines, meter circuits, and metering means which closes circuits only for the meters of calling 35 lines extended through a two-way switch.
18. In a system for interconnecting lines by electro-mechanically controlled switches, non-numerical switches, group-selectors comprising normally open contacts, connectors, talking path through said group-selectors, wanted lines, calling lines, a ringing current machine, meters associated with said lines, means for applying ringing current to wanted lines, means for closing a normally 40 open contact when a wanted line responds to a ringing current, and means for actuating a meter when a wanted line responds.
19. In a system for interconnecting lines by electro-mechanically controlled switches, 45 group-selectors comprising contacts through which calling and wanted lines are interconnected, connectors, calling lines, meters associated with said lines, a ringing current source connected to said group-selectors, said contacts at the group-selectors being controlled by ringing current flowing from a group selector to a wanted subscriber, and means for actuating said meters.
20. In a system for interconnecting lines by 50 electromechanically controlled switches, connecting switches, subscribers' lines, meters associated with said lines, means for applying ringing current to a wanted line, interrupting means for periodically disconnecting the ringing current from the wanted 55 lines, maintaining means for maintaining the application of the said ringing current to the wanted line when said applying means becomes inactive, means for keeping the maintaining means active during the 70 periodic disconnections of the maintaining means, and metering means operating after the maintaining means for actuating said meters.
21. In a system for interconnecting lines 75 by electro-mechanically controlled switches, connecting switches, subscribers' lines, meters associated with said lines, means for applying ringing current to a wanted line, interrupting means for periodically disconnecting the ringing current from the wanted line, maintaining means for maintaining the application of the said ringing current to the wanted line when said applying means become inactive, means for keeping the 80 maintaining means active during the periodic disconnections of the maintaining means, disconnecting means for disconnecting the maintaining means from the wanted line, and metering means operating after the 85 maintaining means for actuating said meters.
22. In a system for interconnecting lines 90 by electromechanically controlled switches, subscribers' lines, meters assigned to the 95 subscribers' lines, group-selectors, connectors with movable contacts, connecting circuits leading to group-selectors, means for applying ringing current to a connecting circuit, means for opening the connecting circuit 100 immediately before the application of the ringing current, means for moving a group selector onto an idle connector, means in the group selector for extending the connecting circuit to the connector, contact-group-selecting means for moving the contacts of the connector onto a group of contacts containing the contacts of the wanted line, line selecting means comprising circuits for moving the connector contacts onto the contacts 105 of the wanted line, controlling means for controlling the circuits of said line selecting means, connecting means in the connector for extending said connecting circuit to the controlling means, said connecting 110 means being actuated after the operation of said contact-group-selecting-means, and metering means operating after the contact-group-selecting-means for actuating said meters.
23. In a system for interconnecting lines 115 by electromechanically controlled switches, calling lines, wanted lines, meters associated with said lines, a first group of circuit-extending switches, a second group of circuit-extending switches, fixed contact rows and movable contacts in each of said circuit-extending switches, contact-row-selecting means in each circuit-extending switch, link-circuits extending from the fixed contacts 120
- 125
- 130

of the first group of circuit extending switches to the movable contacts of the second group of switches, subscribers' lines, extending means for extending a subscriber's line through an extending switch of the first group to an extending switch of the second group, operating means for causing the operation of the contact-row-selecting-means in a switch of said second group and for opening a link circuit extending to said switch from a switch of the first group, applying means for applying ringing current to said link circuit after it is opened, a third group of circuit extending switches with

contact-row-selecting-means, means for extending said link circuit through an extending switch of the third group after the operation of its contact-row-selecting-means, and metering means for bringing the meter of a calling line into operative relation with a wanted line. 15

In witness whereof I have signed this specification in the presence of two witnesses.

FRITZ ALDENDORFF.
